DISH DRAIN OR SIMILAR ARTICLE

Anthony J. Iorio, North Providence, R.I., assignor to United Sterilite Corporation, a corporation of Massachusetts

Filed Jan. 13, 1969, Ser. No. 15,315

Term of patent 14 years

Int. Cl. D7—99

U.S. Cl. D44—29

FIG. 1

FIG. 4

FIG. 1 is a perspective view of a dish drain showing my new design;

FIG. 2 is a fragmentary top plan view of the flatware receiving portion;

FIG. 3 is a front elevational view; and

FIG. 4 is a fragmentary perspective view of the dish holding portion.

I claim:

The ornamental design for a dish drain or similar article, substantially as shown.
